UNITED STATES PATENT OFFICE.

ANSON J. BENTLEY, OF NILES, OHIO.

FREEZING CAN.

Original application filed December 27, 1920, Serial No. 433,163. Divided and this application filed April 28, 1922. Serial No. 557,144.

To all whom it may concern:

Be it known that I, ANSON J. BENTLEY, a citizen of the United States, and a resident of the city of Niles, in the county of Trumbull and State of Ohio, have invented an improvement in Freezing Cans, of which the following is a specification.

The present invention relates to improvements in freezing cans for use in the manufacture of ice and particularly to an improved construction of can wherein means are provided for introducing air into the can to agitate the water which is to be frozen; this being the commonly accepted practice in what is known as the raw water can system of ice making.

This application is filed as a division of an earlier application filed by me on December 27, 1920, Serial No. 433,163. That application showed several embodiments of the invention disclosed therein and the present application will be confined to one of those embodiments. The claims appended hereto will be directed to the particular embodiment of the invention shown herein; the invention common to the several forms being claimed in the above mentioned application.

In the raw water can system of ice making it is customary to immerse freezing cans in an appropriate freezing solution such as brine, and circulate this freezing solution around the cans. In order that the impurities commonly present in water available for the manufacture of ice may not be frozen into the finished cake, the water is agitated during the freezing operation. This agitation may be effected by an air current and the action is such that the impurities are not frozen into the cake but are collected in the small amount of water which remains unfrozen in a pocket in the ice cake at the termination of the freezing period.

In order to introduce this air current it has been customary to provide some sort of a separable tube or pipe extending from the top edge of the can downwardly to a point at or near the bottom and there opening into the interior of the can. This tube or pipe was so arranged that its upper end

could be connected with a source of compressed air and when the can was in use, air was forced through the tube out into the water, thus agitating it with the result above described. As pointed out in my earlier application, freezing cans so constructed have proved unsatisfactory for several reasons. If the tube or pipe is located on the outside of the can it is apt to be jammed or torn loose or otherwise injured as the cans are being handled. The liability to injury of any exposed part of the can will be immediately apparent when it is borne in mind that these cans usually contain three hundred or more pounds of water or ice as the case may be. If the air tube is located inside the can it is very apt to be injured during the freezing of the water or to be torn loose when the ice cake is dumped out of the can.

It is an object of the present invention so to construct a freezing can that a conduit for the introduction of air may be provided without the use of the usual separate tube or pipe, thus providing a distinctly superior construction and at the same time effecting a substantial economy in manufacture.

The embodiment of the invention which has been made the subject matter of this application is shown in the accompanying drawings wherein,

Figure 1 is a perspective view of a freezing can illustrating a preferred form of the invention selected for this application,

Figure 2 is a similar view of the inside of the can shown in Figure 1,

Figure 3 is an enlarged perspective view showing the construction of the air conduit, and

Figure 4 is a similar view showing a slight modification.

The general construction of the freezing can shown herein may be that of letters patent No. 1,027,802, dated May 28, 1912, in so far as the formation of the side walls and the bottom and the joining of the several parts are concerned.

The can shown may comprise two pieces of galvanized sheet metal, one of which forms the side wall 1 and the end wall 2, 100

while the other forms the side wall 3 and the end wall 4. A third piece of sheet metal may be suitably shaped to form the bottom 5 of the can. The side walls may be formed, if desired, with grooves 6 in order to stiffen them.

For convenience in manufacture the seams of freezing cans of the type here shown are usually formed at diagonally opposite corners although a seam or seams might be located elsewhere. In this respect the can shown in the drawings is of the usual construction. The air conduit presently to be described, is conveniently formed adjacent 10 one of the seams. Obviously a conduit might be provided adjacent another seam, if desired.

To provide the embodiment of the present invention herein described, the vertical edge 20 of a side wall member 3 is abnormally extended and folded back upon itself. As illustrated, this folding is done in a direction which will ultimately be toward the interior of the can. Thus a conduit 7 extending 25 substantially the entire length of the wall member 3 will be formed.

In order to provide an opening for the escape of air into the can, the lower end of the folded portion may be cut away as indicated in Figure 3 thus leaving an opening 30 8; or if desired, the folded over portion may extend substantially the entire length of the side 3 and a hole 9 may be formed toward the lower end of the conduit as clearly shown 35 in Figure 4. If it is desired to provide more than one opening for the escape of air, other holes may be made in the conduit.

The conduit having been suitably formed in the manner indicated, the can may be 40 assembled in accordance with the usual practice, that is to say, the side walls may be brought together and riveted where they overlap. The rivets along that seam shown in Figures 3 and 4 will pass through three 45 thicknesses of metal, thereby holding the folded back extension, the side wall 3 and the end wall 2 securely together. The side seams may be rendered fluid tight by soldering in the usual manner.

50 The bottom may now be assembled with the side walls, riveted in place and the bottom seams soldered. The bottom of the can when it is assembled with the sides will constitute an end wall of the conduit 7; the 55 opening in the conduit as shown in Figure 3 being at its lowermost end and as shown in Figure 4 slightly spaced from the lower end. The usual reinforcing band may be placed around the top of the can and suitably riveted 60 in place.

An appropriate fitting designed to cooperate with the particular system in which the can is to be used may be suitably attached to the upper opening of the air conduit.

It will be observed that the construction just described provides a very durable means of introducing air into the can. The walls of the air conduit are of the same strength as the walls of the can itself and there is little or no danger of the conduit becoming jammed so as to interfere with the passage of air therethrough. Moreover there is no tube or pipe exposed on the outside of the can.

75 It is to be understood that the invention may be variously modified and embodied within the scope of the subjoined claims.

I claim as my invention:

1. As an article of manufacture, an ice 80 mould having a portion of one of the walls bent over upon itself to form an air pipe, common means for securing said bent-over portion and an adjacent wall of the tank together, substantially as described.

85 2. A container for use in the manufacture of ice having a wall member abnormally extended beyond a seam in a wall of said container, a part of said extension being folded back toward said seam and riveted near its edge to said wall member to form a complete fluid tight conduit extending from the top substantially to the bottom of the container whereby air under pressure may be introduced into said container to agitate water 95 that is to be frozen therein.

3. A freezing can for use in the manufacture of ice having an integral air conduit extending vertically along a wall of the can and formed by a folded edge portion of a 100 wall member, and a means uniting both the folded edge portion to itself and to another edge portion of a wall member.

4. A freezing can for use in the manufacture of ice having an interiorly located integral air conduit extending vertically along a wall of the can and formed by a folded edge portion of a wall member, and a means uniting both the folded edge portion to itself and to another overlapping edge portion.

105 5. A freezing can for use in the manufacture of ice having an edge portion of a wall member bent back upon itself and spaced along the bend to form an air conduit and common fastening means for securing together the two thicknesses of said folded portion and another edge portion, the said conduit having an opening near the bottom of the can.

110 6. A container for use in the manufacture of ice having a wall member formed with an integral extension beyond a seam, a part of said extension being folded inwardly and back upon itself in the direction of the seam, spaced adjacent the bend and securely fastened at its edge to the main wall member, thereby forming a complete fluid tight conduit having an opening near the top of the container, extending downwardly and having another opening adjacent the bottom of

the container, whereby air under pressure may be introduced into said container to agitate water that is to be frozen therein.

7. A freezing can for use in the manufacture of ice having an integral air conduit extending vertically along a wall of the can and formed by an inwardly folded edge portion of a wall member and common means

uniting both the folded edge portion to itself and to another edge portion of a wall member.

In testimony whereof, I have signed my name to this specification this 24th day of April, 1922

ANSON J. BENTLEY.
